ARTIFICIAL FISHING WORM OR SIMILAR ARTICLE

Thomas J. Hanna, 685 Johnson Road,
Jonesboro, Ga. 30236

Filed May 5, 1975, Ser. No. 574,736

Term of patent 14 years

Int. Cl. D22—05

U.S. Cl. D22—27

FIG. 1 is a pictorial view of an artificial fishing worm embodying the design of the present invention, as curvilinearly disposed;

FIG. 2 is an end elevation view of the relatively blunt head end of the artificial fishing worm;

FIG. 3 is an end elevation view of the J-shaped tail end thereof;

FIG. 4 is a front elevation view thereof, as linearly positioned; and

FIG. 5 is a top plan view thereof, as seen with respect to the linear position depicted in FIG. 4.

I claim:

The ornamental design for an artificial fishing worm or similar article, substantially as shown.
